GASOLINE PUMP

Charles E. Hutchins, Fort Wayne, Ind., assignor to Bowser, Inc., Fort Wayne, Ind., a corporation of Indiana

Application September 8, 1958, Serial No. 52,543

Term of patent 14 years

(Cl. D52—2)

The figure is a perspective view taken from the front and to one side of a gasoline pump showing my new design. The opposite side is substantially of the same appearance as the side shown except that the vertical bars, hose and side openings are omitted. The rear portion has the small window arrangement as on the front and is substantially of the same appearance as the front shown.

I claim:

The ornamental design for a gasoline pump, as shown and described.
